UNITED STATES PATENT OFFICE.

WALTER D. GRIPPEN, OF BINGHAMTON, NEW YORK.

CLOTHES-LINE AND ROPE ADJUSTER.

1,178,716.

Specification of Letters Patent. Patented Apr. 11, 1916.

Application filed July 25, 1914. Serial No. 853,090.

To all whom it may concern:

Be it known that I, WALTER D. GRIPPEN, a citizen of the United States, residing at Binghamton, in the county of Broome and 5 State of New York, have invented certain new and useful Improvements in Clothes-Line and Rope Adjusters, of which the following is a specification.

My invention relates to an improvement 10 in clothes line and rope adjusters, in which the line is automatically gripped and held by the tension of the line itself and it has for its object to provide a light and readily manufactured stretcher readily adjustable 15 and to enable an easy adjustment of the line for clothes lines or other ropes.

With this object in view my invention 20 consists of certain novel features of construction and arrangement of parts as will be hereinafter fully described and pointed out in the claims, reference being had to the accompanying drawings in which—

Figure 1 is a side view of my device in perspective. Fig. 2 is a top plan view of my 25 device. Fig. 3 is a bottom plan view of my device.

The same reference characters denote like parts in each of the several figures of the drawings.

30 In carrying out my invention I provide a curved body portion A, having at one end the eye 2 and having projecting from its sides the pivots 3.3 and having at the opposite end the eye 4. On the lower side I have 35 the parallel projecting opposite lugs 5.5. Also I have formed in it, the curved channel 7, adapted to receive a cord or line 8 and between the projecting lugs 5.5 I have the channel 9. Mounted over the body A, I 40 have pivotally mounted the lever member B, having at one end the cross bar b and at the other end the eye 6. On the sides of the lever member B, I have the sockets C.C adapted to receive the pivots 3.3.

45 In the operation of my device I tie in any convenient manner in eye 2, in body A, the rope 8. I then pass the end of the oppo-

site section of rope 8' to be adjusted, through the eye 6 of the lever member B, and through the eye 4 of the body member A, thence 50 through the notch 7 of the body A, thence under the bar b of the lever member B and through the channel 9 between the lugs 5.5, drawing it up until the rope is stretched to the required point. By this tension the rope 55 8' bearing on the lever member B pivoted on A, it draws the two members together and draws bar b down on the rope 8' and holds it firmly against the surface of A and in channels 7 and 9 between lugs 5 and 5' and 60 the greater the tension the more firmly is the rope held, the channel 7 forming a pocket in which the rope is pressed by the pressure of the bar b. To release rope 8 I raise the lever member B opening the ends 65 of B and A thus releasing the pressure of bar b and the rope may thus be again moved for adjustment.

Having thus described my invention, what I claim as new and for which I desire 70 Letters Patent is as follows:

In a device of the class described, a body member provided at one end with an eye in which the end of a rope is secured, said body member being provided at its other end with 75 an eye through which the rope to be adjusted is passed, the under side of the body member being provided with a longitudinal channel to receive the rope to be adjusted, a lever member pivoted to the body member 80 and provided at one end with an eye through which the rope to be adjusted is passed, said lever member having at its other end a bifurcation which straddles the body member, and a cross bar connected with the ends of 85 the bifurcation and coöperating with the channel in the body member to clamp the rope therein.

In testimony whereof I have affixed my signature in presence of two witnesses.

WALTER D. GRIPPEN.

Witnesses:

S. A. VALENTINE,
E. A. JOYNER.
